UNITED STATES PATENT OFFICE.

JOSEPH A. PAQUETTE, OF NEW MILFORD, CONNECTICUT.

PLASTERER'S TOOL.

Application filed February 9, 1928. Serial No. 253,022.

This invention relates to a plasterer's tool, and has for an object to provide an improved tool of this character which may be used to simultaneously finish both walls forming a corner so as to give a better and more uniform finish to it.

It is also an object of the invention to provide a tool which is adapted for more convenient use for finishing wall surfaces back of obstructions, such as steam pipes and the like.

It is a further object of the invention to provide a tool which is adapted for more uniform and better finishing corners of plaster of Paris moldings and the like.

With the foregoing and other objects in view, I have devised the construction illustrated in the accompanying drawing forming a part of this specification. In this drawing,

Fig. 1 is a top plan view of my improved plasterer's tool.

Fig. 2 is a front elevation thereof, and

Fig. 3 is an end elevation showing how it is used in finishing the walls forming a corner.

The tool as shown, comprises an oblong body portion 10 having on its under side a flat surface 11 for finishing flat wall surfaces, and this body portion is beveled or mitered in opposite directions at its opposite ends as shown at 12 and 13, for finishing corners of plaster of Paris moldings and the like, the angle of this bevel being at any angle desired but preferably about forty-five degrees.

Along one of the side edges, preferably the longer edge, the body portion is provided with an integral flange portion 14 extending at substantially right angles to the body portion and having an outer finishing surface 14 at substantially right angles to the surface 11. This tool may, therefore, be used to simultaneously finish both surfaces 16 and 17 forming a corner, and it will finish these surfaces in a uniform and proper manner giving a much better corner finish and a straight corner line.

If the blade or flange 14 is made about one inch in width it will fit any groove in cornice work or anywhere on panel work. That makes this tool particularly handy and adaptable as the large blade may be used for large surfaces and then the small blade can be used for this special work. Therefore, this small tool may be used for a number of

different kinds of work which with the old tools required the use of a number of different tools. This tool will, therefore, effect a great saving in time as it is not necessary for the mason to change tools, and fewer tools are required in the kit.

I have also provided an improved handle construction with means for mounting the same which cooperates with this peculiar construction of tool for securing improved operation thereof and facilitating its use under certain adverse conditions. For this purpose I mount on top of the body portion

10 a longitudinally extending dove tail rib or bar 18 which is secured with its narrowest side against the body portion by any suitable means, such as spot welding or riveting. The handle comprises a grip 19 secured to an upright member 20 at one end

which is secured at its lower end to a base member 21 having a longitudinally extending dove tail groove to fit the bar 18, and a wing screw 22 is threaded in this base in position to clamp on top of the bar 18 to firmly secure the handle to the tool and permit its adjustment to different positions.

Ordinarily in trowel constructions the handles are permanently secured to the trowel, and in use of the tool behind steam pipes or other obstructions often greatly curtails the use of the tool. With this arrangement as shown, however, the handle may be adjusted longitudinally of the rib 18, thus varying the effective length of the tool so that it may be inserted different distances behind steam pipes and the like, greatly facilitating finishing surfaces behind such obstructions.

Still further the handle may be removed and reversed, as indicated in dotted lines Fig. 2, so that either end of the tool may be used for insertion behind obstructions, and the flange portion 14 may thus be positioned on either side of the handle making it either a right hand or left hand tool.

Another advantage is that other mason's tools, such as ordinary plasterer's trowels, jointers, slickers, or joint rakers may be each provided with a dove tail rib similar to 18, and the same handle may be used for all of these tools. This will greatly reduce the necessary space required in a mason's kit bag over what is required with ordinary tools where there is a separate handle permanently secured to each tool and besides it permits adjustment of the handle on the

100

105

110

tool as described. This is merely another advantage of this particular handle and its means of mounting, but it has special advantages in connection with the special finishing tool illustrated as having the beveled ends and the longitudinal finishing flange portion 14 as described.

Having thus set forth the nature of my invention, what I claim is:

- 10 1. A plasterer's tool comprising an oblong body portion and an integral flange portion along one side edge of the body portion, said portions having outer finishing surfaces at substantially right angles to each other, the opposite ends of the body portion

being mitered in opposite directions from the flange portion, and a handle secured to the back of the body portion.

2. A plasterer's tool comprising an oblong body portion and integral flange portion 20 along one side edge of the body portion, said portions having outer finishing surfaces at substantially right angles to each other, one end of the body portion being mitered in a direction away from the flange portion, 25 and a handle secured to the back of the body portion.

In testimony whereof I affix my signature.

JOSEPH A. PAQUETTE.
